By his Attorney Gifford & Full

UNITED STATES PATENT OFFICE.

ROBERT S. KELLEY, OF NEW YORK, N. Y.

SCORE INDICATING AND RECORDING DEVICE.

1,090,626.

Specification of Letters Patent. Patented Mar. 17, 1914.

Application filed September 28, 1912. Serial No. 722,825.

To all whom it may concern:

Be it known that I, ROBERT S. KELLEY, a citizen of the United States, residing at New York city, borough of Manhattan, in the county of New York and State of New York, have invented certain new and useful Improvements in Score Indicating and Recording Devices, of which the following is a specification.

10 My invention relates to a score indicating and recording device, and has been designed by me more particularly for use in the game of golf. It will be understood by reference to the accompanying drawings in which—

15 Figure 1 is a front view of one embodiment of my invention, part of the casing being broken away; Fig. 2, a side view; Fig. 3, a vertical section on the plane of the line 3—3 of Fig. 1; Fig. 4, a similar view on the 20 plane of the line 4—4 of Fig. 1; Fig. 5, an enlarged detail of part of the type wheel mechanism; and Fig. 6, a section on the plane of the line 6—6 of Fig. 5.

Similar reference numerals indicate similar parts in the several views.

25 The parts hereafter described are inclosed within a suitable case 1, preferably of metal, having a hinged section 2 by which access may be had to the platen 3 for removing

30 and replacing the score card carried thereby. The platen is in the form of a cylindrical drum having trunnions supported in openings in the side walls of the casing. As shown in the drawings the side walls are

35 cut out at 4 to permit the ready insertion of the platen within the casing. One trunnion is extended and carries a milled head 5 to provide a convenient means for rotating the platen. To prevent reverse movement

40 of the platen I secure to it at one end a ratchet wheel 6 the teeth of which are engaged by the free end of a spring pawl 7, the other end of said pawl being fixed to the casing. The platen 3 is adapted to receive a score card in the form of a cylinder

45 of paper 8 which may be easily slipped over the platen when the latter is removed from the casing. This printing surface may be ruled both longitudinally and transversely,

50 each transverse division corresponding to the movement of one tooth of the ratchet wheel 6. The longitudinal divisions are designated by suitable numerals or letters, as indicated in Fig. 1, assigned to the players. The hinged section 2 is cut out at 9

so that the printed score may be read upon turning the platen.

The type surfaces are located in the lower part of the casing and comprise a pinion shaft 10 having fixed bearings in the side 60 walls of the casing to prevent rotation. On this shaft I mount a series of number wheels, each unit of the series comprising a printing wheel 11, an indicating wheel 12 and a gear wheel 13, these three parts being preferably made in one piece, although they may be made in separate pieces and secured together by suitable means. There is one set of these printing and indicating wheels for each player and they are assembled upon the 70 fixed pinion shaft 10 as indicated in Fig. 1.

To effect rotation of the printing and indicating wheels I provide a series of pinions 14 fixed to a suitable shaft having bearings in the casing below the shaft 10. Each pinion 14 meshes with a corresponding gear 13. When any one of the pinions 14 is turned, the corresponding printing and indicating wheels will be rotated so that the numbers desired to be printed by the wheels 80 11 will be brought directly under the platen, the user first turning the platen so that the number will be printed in the proper transverse section of the score card. Between the type wheels and the platen is interposed an inked surface 15, preferably a piece of ordinary typewriter ribbon, so that when the type wheels are raised the numbers presented to the platen will be printed upon the score card. 90

To effect the raising of the type wheels I support the shaft 16 of the pinions 14 in elogated bearings 17, as shown in Fig. 2. Similarly the shaft of the fixed pinion 10 is supported in elongated bearings 18 so that 95 a slight upward pressure against the pinions 14 will raise the pinion 10 and the type wheels 11 carried thereby against the inked surface 15, as shown in Fig. 4. The wheels 11 are slightly greater in diameter than the 100 wheels 12 so that the numbers on the peripheries of the latter are not brought into contact with the ribbon 15. Springs 19 fixed to the casing and passing around one of the printing wheels return all of the 105 wheels to normal position upon release of the pressure upon the pinions 14.

To prevent overthrow of the printing wheels I provide the novel construction shown in detail in Fig. 5. As there shown

the side of each printing wheel is cut out at 20 with an opening 21 through to the inner surface of the wheel. Spanning the opening 20 is a spring 22, and between said 5 spring and pinion 10 is a floating dog in the form of a ball 23, or its equivalent, a small cylindrical metal piece, adapted to be retained in the opening 21 between the teeth of pinion 10. As pinion 10 is fast, it is obvious that rotation of a printing wheel, by 10 its pinions 14, will carry the dog 23 from one tooth to the next of pinion 10, the spring 22 permitting the dog to pass over the points of the teeth.

15 The numbers are so arranged on the peripheries of wheels 11 and 12 that when a given number is set on a printing wheel 11 the corresponding number will be visible on the corresponding wheel 12 through openings 24 in the lower part of the case. The player is therefore enabled to see his score 20 without turning the card so as to bring the numbers opposite the sight opening 9. It will of course be understood that if four 25 players are engaged in the game the score at each hole will be set by means of the pinions 14 and the printing of the scores simultaneously effected by an upward pressure upon any one of the pinions 14. If 30 there are but two players the third and fourth printing wheels may be set at zero or any other number which will be printed continuously.

35 While I have described my device as more particularly adapted for use in the game of golf, it is obvious that it may be employed to keep the score of players in other games.

What I claim and desire to secure by Letters Patent of the United States is:—

40 1. A device of the character described comprising a casing, a rotatable printing surface supported in said casing, wheels having thereon type surfaces one for printing and the other for indicating the score, 45 and means for moving the type wheels to effect the printing of a given number.

2. A device of the character described comprising a casing, a rotatable cylindrical platen supported in said casing, a score card 50 detachably mounted on said platen, a type surface below said platen, and means for adjusting said type surface and for moving it to effect the printing of a given number.

3. A device of the character described 55 comprising a casing, a rotatable platen having a score card supported thereon, printing and indicating wheels mounted below said platen, and means for adjusting and mov-

ing said wheels so as to print a desired number and to visually indicate the number 60 through a sight opening.

4. A device of the character described comprising a casing, a rotatable platen having a removable score card thereon, a printing and indicating mechanism comprising 65 wheels having numbers on their peripheries, and means for adjusting and moving said wheels to effect the printing of a given number and to visually indicate the number 70 through a sight opening.

5. A device of the character described comprising a casing, a rotatable platen having a removable score card thereon, type surfaces comprising a printing wheel and an indicating wheel, a shaft on which said 75 wheels are mounted, and means for moving said wheels to effect the printing of a given number on the score card and to visually indicate the number through a sight opening.

6. A device of the character described comprising a casing, a rotatable platen having a removable score card thereon, printing and indicating wheels mounted below said platen, a gear wheel secured to said wheels, 85 and a pinion meshing with said gear wheel for the purpose of adjusting said printing and indicating wheels, and means permitting the movement of said printing wheel to effect the printing of a given number on the 90 score card.

7. A device of the character described comprising a casing, a rotatable platen having a removable score card thereon, a pinion shaft supported in bearings in said casings and fixed against rotation, a printing wheel rotatably mounted on said shaft, and a floating dog between said wheel and pinion shaft to prevent overthrow of the printing wheel.

100 8. A device of the character described comprising a casing, a rotatable printing surface supported in said casing, a type wheel mounted below said printing surface, said wheel having an opening in its side, a floating dog in said opening resting between the teeth of said shaft, and a spring adapted to exert pressure on said dog.

In testimony whereof I have hereunto signed my name in the presence of two subscribing witnesses.

ROBERT S. KELLEY.
